CLAIM

The ornamental design for an LED round high bay, as shown and described.

DESCRIPTION

FIG. 1 is a front view of an LED round high bay showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a rear, top perspective view thereof.

In the drawings, the broken lines depict portions of the LED round high bay that form no part of the claim. Furthermore, the portions of the view in FIG. 1, shown by a lower tonal value and bordered by broken lines, form no part of the claim.

1 Claim, 7 Drawing Sheets
